United States Patent Office

Des. 219,160
Patented Nov. 10, 1970

219,160

MODEL RACING CAR

Anthony Colin Bruce Chapman, Norfolk, England, assignor to Lotus Components Limited, Norfolk, England
Filed Dec. 18, 1969, Ser. No. 20,557

Claims priority, application Great Britain June 19, 1969

Term of patent 7 years

Int. Cl. D21—02

U.S. Cl. D34—15

FIG. 1 is a top plan view of the model racing car,
FIG. 2 is a front elevation,
FIG. 3 is a side elevation,
FIG. 4 is a rear elevation.
The opposite side of FIG. 3 is identical to the side shown.

I claim:
The ornamental design for a model racing car, as shown and described.
